(57) **CLAIM**

The ornamental design for a wire grating structure, as shown and described.

DESCRIPTION

This application is a divisional application of U.S. application Ser. No. 29/597,429 filed Mar. 16, 2017, the contents therein are incorporated by reference in their entirety.

FIG. 1 is a perspective view of a wire grating structure showing our new design;

FIG. 2 is a top plan view thereof;

FIG. 3 is a front elevation view thereof, the rear elevation view being a mirror image thereof;

FIG. 4 is a right side elevation view thereof, the left side elevation view being a mirror image thereof;

FIG. 5 is a perspective view of an alternative embodiment of the wire grating structure showing our new design;

FIG. 6 is a top plan view thereof;

FIG. 7 is a front elevation view thereof, the rear elevation view being a mirror image thereof; and,

FIG. 8 is a right side elevation view thereof, the left side elevation view being a mirror image thereof.

The broken lines depicting the remainder of the wire grating structure show features that form no part of the claimed design.
